(57) **CLAIM**

The ornamental design for an eyewear holder, as shown and described.

DESCRIPTION

FIG. 1 is a perspective view of an eyewear holder showing my new design;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is a second perspective view thereof, shown in an open configuration.

The broken lines shown represent unclaimed subject matter and form no part of the claimed design.

1 Claim, 8 Drawing Sheets

FIG. 1
